UNITED STATES PATENT OFFICE.

CHARLES R. HRONISH, OF KNIFE RIVER, NORTH DAKOTA.

HOG-SCALDING APPARATUS.

1,079,648.

Specification of Letters Patent. Patented Nov. 25, 1913.

Application filed April 25, 1913. Serial No. 763,617.

To all whom it may concern:

Be it known that I, CHARLES R. HRONISH, a citizen of the United States, residing at Knife River, in the county of Dunn and 5 State of North Dakota, have invented certain new and useful Improvements in Hog-Scalding Apparatus; and I do hereby declare the following to be a full, clear, and exact description of the invention, such as 10 will enable others skilled in the art to which it appertains to make and use the same.

This invention comprehends improvements in hog scalding apparatus and has for its primary object the provision of simple means whereby a hog may be easily turned over within a scalding tank.

Another and more specific object of the invention is to provide an apparatus including two endless chains secured to rollers 20 carried adjacent the side of a tank, said chains being adapted to support a hog and turn the same when properly actuated.

The invention also aims to generally improve apparatus of this type to render the 25 same more efficient, more easily operated, and more commercially desirable.

With these and other objects in view, as will become more apparent as the description proceeds, the invention consists in certain 30 novel features of construction, combination, and arrangement of parts, as will be hereinafter described and claimed.

For a complete understanding of my invention, reference is to be had to the following 35 description and accompanying drawings, in which,

Figure 1 is a top plan view of a hog scalding apparatus constructed in accordance with my invention, Fig. 2 is a vertical 40 transverse sectional view therethrough, taken on the plane of line 2—2 of Fig. 1, Fig. 3 is a detail view taken on the plane of line 3—3 of Fig. 1, and Fig. 4 is a section taken on the plane of line 4—4 of Fig. 2.

45 Referring in detail to the drawings by numerals, 5 designates a hog scalding tank, of any preferred construction. In the preferred embodiment of my invention, I provide brackets, generally designated 6, and 50 each formed of a strip of flat metal bent intermediate its ends to provide a pair of essentially parallel arms which are adapted to engage opposite faces of one of the side walls of the tank. Set screws 7 are employed 55 for the purpose of securing the

brackets in position. A shaft 8 is journaled through the brackets and is adapted to be rotated by means of a crank handle 9 secured to one end thereof. A ratchet wheel 10 is rigid with the shaft and is engaged by 60 a pawl 11, which holds the shaft against rotation in one direction. Toothed rollers 12 and 13 are slidably secured to the shaft 8 by means of pins 14 which project into grooves 15 formed therein. It will be noted 65 that these rollers are of a peculiar construction, being formed with relatively deep peripheral channels having teeth formed upon the inner walls thereof. A second shaft 16 is secured upon the opposite side of the tank 70 in parallel relationship to the shaft 8 by means of vertically adjustable brackets 17. These brackets are apertured at their enlarged upper ends to permit the passage 75 therethrough of the shaft and are provided with shanks 18 which are formed with a plurality of openings 19. These shanks are 80 slidable within dove-tail grooves 20 formed in the inner arms of U-shaped members 21, which are secured to the side of the tank 80 by means of set screws 22. The side walls of the grooves 20 are apertured as indicated at 20', to receive locking pins 21' which, by extending through certain of the openings in the shanks 18, will support the latter in 85 any desired position. Rollers 23 and 24 similar in construction to the rollers 13 but of a somewhat larger diameter, are slidably secured to the shaft 16 by means of pins 25 which project into slots 26. A pair of endless chains 27 and 28 run around corresponding 90 rollers upon opposite sides of the tank, and pass transversely through the tank, as clearly shown in Fig. 2.

In operation, a hog is placed across the 95 upper leads of the chains, said chains having been first adjusted so as to have the proper distance between them and then the shaft 8 is rotated by means of the crank handle 9. This rotation of the shaft will cause the 100 chains to run through the tank and they will serve to roll the hog over. When it is desired to raise the hog to the top of the tank, pins are inserted through certain of the 105 openings 29 in the smaller rollers 12 and 13 so as to prevent the chains running over the same, and then by turning the crank handle, the chains will be brought into essentially horizontal planes above the top of the tank. The ratchet wheel 10 and pawl 11 prevent 110

a reverse rotation of the shaft 8 and it will therefore be seen that a hog will be supported upon the upper leads of the chains above the tank. The distance to which the 5 chains descend into the tank may be regulated by raising or lowering the brackets 17.

From the foregoing description taken in connection with the accompanying drawing, it will be seen that I have provided a hog 10 scalding apparatus of extremely simple construction, which may be easily operated by one person so as to lower a hog into the scalding tank, turn the same over therein, and then raise it above the tank.

15 It is to be understood that while I have shown and described the preferred embodiment of my invention, I do not wish to be limited to this exact construction, combination, and arrangement of parts, but may 20 make such changes as will fall within the spirit and scope of the invention.

Having thus described my invention, what I claim is:—

1. In a hog scalding apparatus, the combination with a swinging tank, of a shaft rotatably secured to one side thereof, rollers rigid with said shaft and formed with peripheral channels having teeth formed upon the inner walls thereof, the side walls of 30 said channels being formed with registering openings, means for rotating said shaft, means for locking the shaft against rotation in one direction, a second shaft rotatably supported upon the other side of the tank, 35 grooved rollers rigidly secured to the second mentioned shaft, endless sprocket chains running over corresponding rollers on the two shafts, and means adapted to be inserted through the registering openings in the first

mentioned rollers to prevent the chains running around said rollers. 40

2. In a hog scalding apparatus of the character described, a swinging tank, a shaft rotatably secured to one side thereof, means for rotating said shaft, means for locking 45 the shaft against rotation in one direction, a plurality of rollers rigidly secured to the shaft and provided with peripheral channels having teeth formed upon the inner wall thereof, the side walls of said channels being 50 provided with openings, a second shaft rotatably secured to the other side of the tank, rollers rigidly secured to the second mentioned shaft, endless sprocket chains running over corresponding rollers on opposite sides 55 of the tank, and pins inserted through the openings in the side walls of said channels to lock the chains against movement relative to the corresponding rollers.

3. In a hog scalding apparatus, the combination with a scalding tank, of a shaft supported upon one side thereof, means for rotating said shaft, means for locking the shaft against rotation in one direction, a second shaft secured to the other side of said 65 tank, toothed rollers rigid with the shafts, endless chains revoluble around corresponding rollers and running through the tank, and means for locking the chains to certain 70 of the rollers, whereby the chains may be drawn taut.

In testimony whereof I affix my signature in presence of two witnesses.

CHARLES R. HRONISH.
